UNITED STATES PATENT OFFICE.

THEODORE S. WILKIN, OF MILWAUKEE, WISCONSIN.

SAWMILL SET-WORKS.

SPECIFICATION forming part of Letters Patent No. 777,232, dated December 13, 1904.

Application filed September 22, 1902. Serial No. 124,335. (No model.)

To all whom it may concern:

Be it known that I, THEODORE S. WILKIN, residing at Milwaukee, in the county of Milwaukee and State of Wisconsin, have invented 5 a new and useful Improvement in Sawmill Set-Works, of which the following is a description, reference being had to the accompanying drawings, which are a part of this specification.

This invention involves improved means in 10 set-works for sawmills for adjusting or setting the set-works for setting up the knees the predetermined distance and the means for setting up the knees when the set-works are adjusted.

15 This invention is an improvement on the construction shown and described in the application, Serial No. 94,930, for a patent for set-works for sawmills, filed by me on February 20, 1902, and for which Patent No. 744,449 20 was issued on November 17, 1903.

The invention consists of the mechanism, its parts, and combinations of parts, as herein described and claimed, or the equivalents thereof.

25 In the drawings, Figure 1 is a top plan view of my improved set-works shown in connection with a fragment of the carriage of a sawmill and the knees thereon, whereby the relations of the set-works to the carriage are 30 shown. Fig. 2 is a transverse section on line 2 2 of Fig. 1 of the set-works looking toward the right. Fig. 3 is a view of some parts of the mechanism shown in Fig. 2 as seen from the left of the parts as shown in Fig. 2. Fig. 35 4 shows another form of device for converting rotary into rectilinear motion, which device may be employed in place of the crank near the bottom of the drawing in Fig. 2.

In the drawings, A represents the log-carriage.

B are fragments of the knees, mounted to slide on the head-blocks C C, which head-blocks are rigid on and a part of the carriage.

2 2 are brackets or structure members rigid 45 on and forming a part of the carriage A. A set-shaft 3 is revolute in the head-blocks and in a bracket 2. The set-shaft is provided with pinions at 4 4, that mesh with racks on the under side on the knees B, whereby by the ro-

tation of the shaft the knees are set up or re- 50 turned to initial position.

For rotating the shaft 3 I advisably provide an expansive power medium, preferably steam, and for such medium a cylinder 5, mounted on the carriage A, is employed, which 55 cylinder is provided with a reciprocable piston and means for introducing steam or the expansive medium into the piston on each side thereof. The piston and the means for introducing the steam into the cylinder being a 60 matter of common use are not shown in the drawings. A power-driven shaft 6, advisably made hollow, is mounted revolutely in brackets 2 2 and on and about the shaft 3. This hollow power-driven shaft 6 is rotated by the 65 reciprocating movement of the stem 7 of the piston of the cylinder 5, and therefor racks are employed, preferably on a yoke 8, secured to the piston-stem 7, which racks on the legs of the yoke 8 mesh with pinions 9 9 on the 70 shaft 6. A clutch 10, one member of which is rigid on the extremity of the hollow shaft 6 and the other member of which is splined on the shaft 3, is adapted for coupling the shaft 3 revolutely with the hollow shaft 6. Normally the clutch is out of engagement.

For transmitting the rotary motion of the power-driven shaft 6 to the set-shaft 3 means are employed which are adapted to be so adjusted or set that the rotation of the power-driven shaft 6 one complete revolution will rotate the set-shaft 3 to a predetermined extent in accordance with the position to which the set-works are adjusted or will not rotate the set-shaft 3 to any extent whatever, if desired, and the set-works are adjusted therefor. The length of the racks are such with reference to the pinions on the power-driven shaft 6 with which they mesh that one complete movement of the racks in either direction will rotate the shaft 6 one revolution.

A pinion 11, fixed on the end of power-driven shaft 6, conveniently by casting it integral with the shaft, meshes with a pinion on an intermediate shaft 12, mounted revolutely 95 in brackets 2 2, and the shaft 12 is provided with a crank 13, and a rod 14 connects a wrist-pin on the crank 13 to an anchor-block 15, the

rod 14 being conveniently connected thereto by being pivoted on a stud-pin 16, fixed in the block, and a rod 17 connects the anchor-block 15 by being pivoted on the pin 16 to the wrist 5 on a crank 18 on rock-shaft 19. The rock-shaft 19 is mounted in brackets 22 on the carriage. The anchor-block 15 is mounted slidably on segmental guide 20, and this guide at its lower end is fixed on the axle of hand-lever 21, the axle being mounted revolvably in 10 a bracket 2. The segmental guide 20 and the hand-lever 21 being fixed on a common axle are rigid to each other. A notched and graduated segmental rack 22 is mounted on the carriage conveniently by means of bolts 23 15 23, that secure it adjustable endwise thereto, the bolt 23 at the lower end passing through an ear on the carriage and through an elongated slot in the rack, and the bolt 23 at the upper end passing through an arm 24 projecting 20 upwardly from the carriage and through an elongated slot therefor in the rack 22. The hand-lever 21 straddles and swings on the rack 22, which rack is in an arc concentric to the 25 axle of the hand-lever 21. The hand-lever 21 is provided with spring-held catches 25, adapted to engage concurrently notches on the inner and outer edges of the rack. The rack is provided with such number of notches or 30 teeth, only a few of which are shown, as adapts it for holding the lever at such points as it may be moved to, whereby the set-works may be adjusted for setting up the knees an exact distance from the one thirty-second of an inch 35 to any great extent that would be required in the sawing of lumber.

The rock-shaft 19 is provided with two arms projecting therefrom radially in opposite directions, which are connected by the rods 26 40 26, respectively, to tilting pawls 27 28, both of which engage the ratchet-wheel 29 on the same side thereof. The ratchet-wheel 29 is fixed on the shaft 3. The attendant can lift the pawls 27 28 out of engagement with the 45 ratchet-wheel 29 when it is necessary to rotate the shaft 3 in the opposite direction for returning the knees to initial position.

It should be understood that in use the set-works, by means of shifting the hand-lever 21, 50 are to be set to the position required for moving the knees of the carriage up a predetermined distance, and thereupon by opening the throttle to the steam-cylinder and admitting steam at one side or the other of the piston the yoke 8 will be moved in one direction the extent of its travel, whereby the driven shaft 6 will be rotated one revolution and the set-shaft will be rotated to such extent as corresponds with the position at which the set-works have been set or adjusted. In fact, 55 when the set-works are adjusted in the position shown in Fig. 2, in which the lever-handle 21 is thrown up to its limit of travel, the driven shaft 6 can be rotated without rotating

the shaft 3 to any extent whatever, because 65 in the adjustment shown in Fig. 2 the rotation of the shaft 6 would merely cause the anchor-block 15 to reciprocate on the segmental guide 20 in an arc about the wrist on the crank 18 as an axis, and in such case the crank 18 70 and its rock-shaft 19 would not be oscillated, so that no movement would be communicated therefrom to the set-shaft 3; but when the lever-handle 2 is thrown down to any extent whatever from its highest position the segmental 75 guide 20 is shifted into eccentric or tangential position with reference to the wrist on the crank 18, and thereupon when the driven shaft 6 is rotated the anchor-block 15 will travel in a path eccentric to the wrist on crank 80 18, whereby that crank and the rock-shaft 19 will be oscillated to a corresponding extent, and thereby the set-shaft 3 will be rotated correspondingly. It may also be noted that the set-works always stop at and start from a 85 home position—that is, a position of the shafts 6 and 12 that is identical—being determined by the movement of the piston and its stem 7 in the steam-cylinder to the limit of its travel in one direction, which always brings the shaft 90 6 into the same initial position. From this “home” position the set-works always start when the throttle is opened in making the movement resulting in setting up the knees 95 the predetermined distance.

In Fig. 4 another form of crank device is shown, which may be used instead of the crank 13 on the shaft 12. In this form of device a disk 30 is provided with transverse slots 31 32, crossing each other at right angles at the center of the disk, and sliding blocks 33 34 are adapted to slide, respectively, in the slots 31 and 32, and the rod 14 is pivoted to these two blocks, the blocks being so disposed that when 100 33 is at the center of the disk the block 34 will be at the limit of its travel radially in its channel 32, and when the block 34 is at the center of the disk the block 33 will be at the limit of its travel radially in the slot 31, the blocks between these limits of travel being at 105 corresponding distances from their respective limits of travel. As this form of device shown in Fig. 4 is adapted to produce two reciprocal movements of the rod 14 by one revolution of the disk, the pinion 11 must be made 110 one-half the size it is, as shown in Fig. 2, or the pinion on shaft 12 must be doubled in size to secure a result corresponding with that obtained by the construction shown in Fig. 2.

What I claim as my invention is—

1. In sawmill set-works, means for adjusting the mechanism for setting up the mill-knees a predetermined distance, comprising a rock-shaft having a crank, a rod connecting said crank to an anchor-block, a pivotally-adjustable segmental guide, said anchor-block being reciprocable on said guide the guide being so mounted and adjustable that the block sliding

thereon will move in an arc concentric with the wrist of the crank or eccentric thereto according to adjustment of the guide, a rotating crank, and a rod connecting this rotating 5 crank to said reciprocable anchor-block.

2. In sawmill set-works, means for adjusting the mechanism for setting up the mill-knees a predetermined distance, comprising a rock-shaft having a crank, a rod connecting said 10 crank to an anchor-block, a segmental guide, a hand-lever having a therewith rigid axle on which the segmental guide is fixed the axle being rotatable in a relatively stationary bearing, said anchor-block reciprocable on said 15 guide the guide being so mounted and adjustable that the block sliding thereon will move in an arc concentric with the wrist of the crank or eccentric thereto according to adjustment of the guide, a rotating crank, and a rod 20 connecting this rotating crank to said reciprocable anchor-block.

3. In sawmill set-works, means for adjusting the mechanism for setting up the mill-knees a predetermined distance, comprising a rock-shaft having a crank, means connecting said 25 crank to an anchor-block, a segmental guide, a hand-lever rigid to and movable concentrically with said guide in a relatively stationary bearing, means for locking the guide readily in adjusted position, said anchor-block reciprocable on said guide the guide being so mounted and adjustable that the block sliding thereon will move in an arc concentric 30 with the wrist of the crank or eccentric thereto according to adjustment of the guide, a rotating crank, and means connecting this rotating 35 crank operatively to said reciprocable anchor-block.

4. In sawmill set-works, a set-shaft, a rock-shaft provided with a crank, means connecting the rock-shaft operatively to the set-shaft whereby the oscillation of the rock-shaft will 40 rotate the set-shaft, a reciprocable anchor-block, an adjustable guide for the anchor-block, means connecting the anchor-block to a crank on the rock-shaft, a rotatable shaft, provided with a crank, means connecting the anchor-block with the crank of the rotatable 45 shaft, and a driven shaft geared to said rotatable shaft.

5. In sawmill set-works, a set-shaft, a rock-shaft provided with a crank, means connecting the rock-shaft operatively to the set-shaft whereby the oscillation of the rock-shaft will 50 rotate the set-shaft, a reciprocable anchor- 55

block, a segmental pivoted and adjustable guide for the anchor-block, means connecting the anchor-block to a crank on the rock-shaft, a rotatable shaft, means connecting the anchor-block with the rotatable shaft eccentrically, and a driven shaft geared to said rotatable shaft.

6. In sawmill set-works, a set-shaft, a rock-shaft provided with a crank, means connecting the rock-shaft operatively to the set-shaft 60 whereby the oscillation of the rock-shaft will rotate the set-shaft, a reciprocable anchor-block, a segmental pivoted and adjustable guide for the anchor-block, means for swinging and thereby adjusting said guide and for locking it releasably in adjusted position, means connecting the anchor-block to a crank on the rock-shaft, a rotatable shaft, means connecting the anchor-block with the rotatable shaft eccentrically, and a driven shaft 65 70 75 geared to said rotatable shaft.

7. In sawmill set-works, a set-shaft, a rock-shaft provided with a crank, means connecting the rock-shaft operatively to the set-shaft whereby the oscillation of the rock-shaft will 80 rotate the set-shaft, a reciprocable anchor-block, an adjustable guide for the anchor-block, means connecting the anchor-block to a crank on the rock-shaft, a rotatable shaft, means connecting the anchor-block with the 85 rotatable shaft eccentrically, a driven shaft geared to said rotatable shaft, and reciprocable means adapted by its reciprocation to rotate the driven shaft.

8. In sawmill set-works, a set-shaft, a rock-shaft provided with a crank, means connecting the rock-shaft operatively to the set-shaft whereby the oscillation of the rock-shaft will 90 rotate the set-shaft, a reciprocable anchor-block, an adjustable guide for the anchor-block, means connecting the anchor-block to a crank on the rock-shaft, a rotatable shaft, means connecting the anchor-block with the 95 rotatable shaft eccentrically, a driven shaft geared to said rotatable shaft, and a steam-actuated reciprocable yoke adapted by its movement in each direction to rotate said 100 driven shaft one complete revolution.

In testimony whereof I affix my signature in presence of two witnesses.

THEODORE S. WILKIN.
